[57] CLAIM

The ornamental design for a reel seat with trigger, as shown and described.

DESCRIPTION

FIG. 1 is a perspective view of a reel seat with trigger showing my new design;

FIG. 2 is a front view thereof;

FIG. 3 is a rear view thereof;

FIG. 4 is a side elevational view thereof, the other side being a mirror image;

FIG. 5 is a top view thereof;

FIG. 6 is a bottom view thereof; and,

FIG. 7 is a cross-sectional view taken along the line 7—7 of FIG. 4.

The broken line showing of a fishing rod handgrip portion and blank is for illustrative purposes only and forms no part of the claimed design.
